COMBINED DESK AND SEAT

Theodore C. Knobloch, Detroit, Mich.

Application April 11, 1956, Serial No. 41,022

Term of patent 14 years

(Cl. D33—14)

Fig. 1 is a side elevational view of the combined desk and seat embodying my new design.

Fig. 2 is an end view thereof looking in the direction of the arrow 2, in Fig. 1.

Fig. 3 is a section taken substantially on the line 3—3 of Fig. 1.

I claim:

The ornamental design for a combined desk and seat, as shown.
